UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

DOOR-FRAME AND DOOR STRUCTURE FOR FURNACES.

1,275,943.

Specification of Letters Patent. Patented Aug. 13, 1918.

Application filed December 31, 1917. Serial No. 209,635.

To all whom it may concern:

Be it known that I, LUTHER L. KNOX, a citizen of the United States, residing at Bellevue, in the county of Allegheny and State of Pennsylvania, have invented a new and useful Improvement in Door-Frames and Door Structures for Furnaces, of which the following is a full, clear, and exact description, reference being had to the accompanying drawings, forming part of this specification, in which:

Figure 1 is a front elevation of a door frame and door structure embodying my invention.

Fig. 2 is a top plan view of the same, and

Figs. 3 and 4 are sections taken respectively on the lines III—III and IV—IV of Fig. 1.

My invention has relation to door frame and door structures for furnaces; and is designed to provide a structure of this character having water cooled parts which can be readily formed from sheet metal by bending and welding processes. A further object of the invention is to provide structures of this character in which the door frame and door have co-acting guiding portions of novel and effective character.

The nature of my invention will be best understood by reference to the accompanying drawings in which I have shown a preferred embodiment thereof, and which will now be described, it being premised, however, that various changes can be made in the details of construction and arrangement of the various parts, without departing from the spirit and scope of my invention, as defined in the appended claims.

In these drawings, the numeral 2 designates a portion of the wall of a furnace having therein the usual door opening 3. 4 designates a rigid metallic frame surrounding the door opening, and which may be, in general, of any suitable character. 5 is a hollow water-cooled top or lintel member supported at the upper edge of the door opening 3, between the posts of the frame 4, being secured to said posts by the forwardly projecting extensions 6 of its end plates. 50 This member can be conveniently formed from a sheet metal plate bent upon itself to give it the required hollow cross section, with its free end portions welded together at any suitable point. Its outer face 7 forms 55 a vertical door seating and guiding surface,

while its inner wall 8 is sloped downwardly and inwardly to form a skew-back for supporting the furnace arch 9. The end portions of said member 5 are reduced, as shown at 10, to form guideways for the edges of 60 the door, hereinafter described. 11 designates hollow vertical frame members which extend upwardly, one at each side of the door opening 3. Each of these members may be conveniently formed of a sheet 65 metal plate bent upon itself to give a generally rectangular hollow section with the offset 12 at the inner corner of its outer or front wall. One edge portion of the metal is bent forwardly to form a bolting flange 70 13, which is bolted to the web of the vertical frame member 4. The recesses 14 (see Fig. 3) formed by the forward offsets 12 correspond with the recesses 10 formed by the reduced end portions of the member 5. 75

15 designates the door which is also of hollow sheet metal form shaped on its inner side to form a pocket or recess for the reception of the refractory lining 16. The door may be conveniently built up from sheet 80 metal plates, flanged to form, the edge forming flanges 17 of the outer plate being extended beyond the seating flanges 18 of the inner plate and into the recesses 10 and 14, before described, to act as guides. The bottom plate of the door is preferably inclined 85 upwardly and inwardly, as shown at 19, so that when the door is seated in vertical position upon the sill 20, the seating will occur at a point near the outer edge of the door 90 and outside of its center of gravity. This tends to hold the door in its closed position and to prevent it from tipping away from its seating surfaces on the frame.

21, wherever seen, designates inlet connections for supplying water to the hollow water cooled members, and 22 designates outlet connections for the heated water. These connections may be of any suitable character.

My invention provides a frame and door structure for furnaces in which the parts subject to the greatest heat and greatest wear may be effectively water cooled; in which the water cooled parts can be readily formed from sheet metal; and in which the door is properly seated, centered and guided.

I claim:

1. The combination with a door frame having vertical water cooled members, each 110

of which is formed with a guiding offset at the inner corner of its outer side, of a hollow water cooled door having its end walls extended inwardly in the edgewise plane of said walls and beyond its seating faces, said extensions co-acting with said offsets to form guiding means for the door, the door and door frame having abutting seating portions adjacent to the end-wall guiding extensions; substantially as described.

2. The combination with a door frame having vertical water cooled members, each of which is formed with a guiding offset at the inner corner of its outer side, of a hollow water cooled door having its end walls extended inwardly beyond its seating faces, said extensions co-acting with said offsets to form guiding means for the door, the frame also having a top member formed with reduced end portions lying above the guiding recesses formed by the offsets in said vertical members; substantially as described.

3. The combination with a door frame 25 having vertical hollow water cooled members formed each with a hollow offset portion at the inner corner of its outer face, one face of the offset forming a door seating surface, and the other face a door guiding surface, of a door having co-acting seating surfaces and co-acting rearwardly projecting guiding flanges, the door-seating surfaces hung inside of and independent of the said guiding flanges; substantially as described. 30

4. In a door frame structure for furnaces, a hollow water cooled member whose body portion is formed from a metal sheet or plate bent upon itself to form a generally rectangular hollow section with an angular 40 hollow offset at the inner corner of its outer side, one edge portion of said sheet or strip being extended outwardly to form a vertical attaching flange; substantially as described.

In testimony whereof I have hereunto set 45 my hand.

LUTHER L. KNOX.
